(57) **CLAIM**

The ornamental design for a distal cutting block, as shown and described.

DESCRIPTION

FIG. 1 is a front perspective view of a design of a first embodiment of the distal cutting block;

FIG. 2 is a top plan view of the distal cutting block of FIG. 1;

FIG. 3 is a bottom plan view of the distal cutting block of FIG. 1;

FIG. 4 is a first side elevation view of the distal cutting block of FIG. 1;

FIG. 5 is a second side elevation view of the distal cutting block of FIG. 1;

FIG. 6 is a front elevation view of the distal cutting block of FIG. 1;

FIG. 7 is a rear elevation view of the distal cutting block of FIG. 1;

FIG. 8 is a front perspective view of a design of a second embodiment of the distal cutting block;

FIG. 9 is a top plan view of the distal cutting block of FIG. 8;

FIG. 10 is a bottom plan view of the distal cutting block of FIG. 8;

FIG. 11 is a first side elevation view of the distal cutting block of FIG. 8;

FIG. 12 is a second side elevation view of the distal cutting block of FIG. 8;

FIG. 13 is a front elevation view of the distal cutting block of FIG. 8; and,

FIG. 14 is a rear elevation view of the distal cutting block of FIG. 8.

The features shown in broken lines depict environmental subject matter only and form no part of the claimed design in the embodiments in which they are shown.
